UNITED STATES PATENT OFFICE.

ABRAHAM BRUEGGER, JR., GEORGE E. PRESTON, AND CHARLES HICKS, OF CHICAGO, ILLINOIS, ASSIGNEES TO E. B. PRESTON, OF SAME PLACE.

DESIGN FOR A HOSE-CARRIAGE BODY.

SPECIFICATION forming part of Design No. 18,612, dated September 18, 1888.

Application filed April 10, 1887. Serial No. 235,125. Term of patent 14 years.

To all whom it may concern:

Be it known that we, ABRAHAM BRUEGGER, Jr., GEORGE E. PRESTON, and CHARLES HICKS, citizens of the United States, residing in Chicago, in the county of Cook and State of Illinois, have invented a new and original Design 5 for a Hose-Carriage Body, of which the following is a specification.

In the accompanying photographic prints, forming a part of this specification, Figure 1 is a perspective view, looking from the front corner, of a hose-carriage body showing our design; and Fig. 2 is a similar view from the opposite side, looking from the rear corner.

15 The leading feature of our design consists in the arch D of said body, terminating at its front end in a horizontal portion extending forward beneath the seat, where it is met at an angle by the vertical portion d² of the frame.

20 Minor features of our design consist in the reticulated panels a, surmounting said arch D;

in the ornamentation, b, of that portion of the body which extends from one of the vertical parts, d², to the other, said ornamentation consisting in the open scroll-work shown in the 25 contour, c c', of the top of the casing, which is situated upon the upper side of the horizontal portion D' of the body; in the vertical rods or posts d, rising from said portion D' and having the swells d' d², and in the horizontal transverse portion extending between said posts d and having the swell g.

What we claim is—

The design for a hose carriage body herein described, and shown by the accompanying 35 photographic prints.
